UNITED STATES PATENT OFFICE.

WALDEMAR KOPS, OF NEW YORK, N. Y., AND HARVEY GILES, OF BOUND BROOK, NEW JERSEY, ASSIGNEES TO KOPS BROS., OF NEW YORK, N. Y., A FIRM.

BUCKLE.

1,142,523.

Specification of Letters Patent. Patented June 8, 1915.

Application filed April 23, 1913. Serial No. 762,974.

To all whom it may concern:

Be it known that we, WALDEMAR Kops and HARVEY GILES, both citizens of the United States, residing, respectively, in the borough 5 of Manhattan, in the city, county, and State of New York, and at Boundbrook, in the county of Somerset and State of New Jersey, have invented an Improvement in Buckles, of which the following is a specification.

10 Our present invention relates to an improvement in buckles, particularly adapted for use in connection with hose supporters, suspenders, and other like garments and articles of wearing apparel, in connection with 15 which it is necessary to adjust the fastening devices to a desired position.

Our present invention relates particularly to that class of buckles in which, in conjunction with a body member, is employed 20 a slideable member, and in accordance with our invention this slideable member is so constructed as to receive and have connected thereto the end of the web or belt with which the buckle is employed, and in the 25 use of which, when tension is applied, the slideable member is moved, as a result of the tension, into contact with a portion of the web or belt on the inner side thereof adjacent to where the same passes through the 30 body member of the buckle to hold the parts in position, whereas when the tension is released the slideable member may be moved in the opposite direction and away from this portion of the web or belt so that the latter 35 may be slipped readily through the body portion of the buckle and adjusted to the desired position therein, all of which will be hereinafter more particularly described.

In the drawing, Figure 1 is a plan view of 40 the blank from which the body member of our improved buckle is made. Fig. 2 is a similar view of the movable member. Fig. 3 is a side elevation illustrating the use of the buckle in a hose supporter. Fig. 4 is a 45 front elevation of the same. Fig. 5 is an enlarged cross section on the line 5, 5, Fig. 3, and Fig. 6 is an enlarged cross section through the slideable member, showing the manner in which the end of the web or strap 50 is connected to the same.

Referring to the drawing, and particularly to Figs. 1 and 2, our improved buckle preferably comprises a body member which may be stamped up from sheet metal so as

to consist of a blank 10 comprising side or 55 end members 11 and 12, transverse or connecting members 13 and 14, and an intermediate transverse member 15, apertures 16 and 17, respectively, resulting between the members 13 and 15 and the members 14 and 60 15. The end members 11 and 12, in similar positions, are provided with tongues or extensions 18 and 19 which are turned over on approximately the line 20 so as to form 65 guide-ways for a movable member, as hereinafter described. The transverse member 13 is also preferably inturned slightly on approximately the line 21, so that the inner 70 upper edge of this member forms a gripping edge for the fabric or other material employed with the buckle. Similarly the transverse member 14 is slightly inturned approximately on the line 22 for a similar purpose.

The blank forming the slideable member is 75 indicated at 23, special reference being made to Fig. 2. This blank is cut along the lines 27 and the parts thereof turned over on each other so as to provide an obverse side 24 and a reverse side 25, the blank thereby being 80 provided with a series of teeth 29 forming a serrated edge and an intermediate series of recesses 28, the teeth 29 remaining in alignment with the obverse side 24 while the major portion of the recesses lie in the 85 turned portion of the reverse side 25. At either end the obverse side 24 is provided with tongues or projections 26, extending the side edges of the obverse side 24, making 90 slides of the same which are adapted to 95 move within the slide-ways provided by the over-turned projections 18 and 19 in the body of the buckle.

In the use of the hereinbefore described buckle, one end of the web or other material 95 employed with the same, as indicated at 30, is secured between the obverse and reverse sides of the slideable member. This may be accomplished in any manner well known in the art. The web 31, or other material, is 100 then passed through the loop 32 of the garment clasp 33 or other fastening device, and after the slideable member has been inserted in position with the slide at the ends thereof within the slide-ways at the ends of the body 105 member, the opposite end of the web 31 is passed from the inside through the aperture 17, in the body of the buckle, and then from

the outside to the aperture 16 in the body of the buckle, whereupon the device is then in position for use.

As will be apparent by reference to the drawing, when the tension is applied to the web in use, the same will cause the movable member to slide within the slide-ways, bringing the serrated edge or teeth thereof in contact with the inner surface of the web adjacent to that point where the same passes through the aperture 17, and this serrated edge is so gripped to the fabric as to hold the parts in the desired position, whereas when the tension is released the 10 slidable member is moved in the opposite direction so that the serrated edge or teeth 29 of the slidable member will be moved away from contact with the inner surface of the web or other material when, it will be understood, the same may be freely adjusted to position by being passed in one direction or the other through the apertures 16 and 17, through which it is threaded.

It will also be noted that the end of the web or other material is so secured in the slidable member, and the slidable member so placed in the body of the buckle that the end of the web adjacent to the point where it leaves the slidable member is over-turned 25 against one edge thereof. This, as will be understood, provides a binding action between the fabric in the movable member, tending to relieve the pull of the fabric and thus assist in maintaining the end thereof 30 within the slidable member. It is further to be noted that the parts are so constructed

that after the web or other material is passed through the member of the buckle, the material itself forms a stop which limits the extent of the movement in the slidable member within the slide-ways of the body of the buckle. 40

We claim as our invention:

A buckle comprising a body member having transverse parallel slots therein and overturned parts at the sides to form slide-ways with the adjacent portions thereof, a U-shaped gripping member separable from the body member and adapted at its ends to fit and move within the said slide-ways, a series of teeth stamped from the reverse side of the said gripping member and lying in substantially the same plane as the obverse side thereof, and a strip of material secured at one end between the parts of the U-shaped gripping member folded over the edge of the reverse side thereof and threaded through one of the slots in the body member from the rear thereof and through the other slot in the body member from the front thereof so that the gripping member lies between and is maintained in position in the body member by those portions of the said strip of material which are threaded through the slots of the body member. 50 55 60 65

Signed by us this third day of April 1913.

WALDEMAR KOPS.
HARVEY GILES.
